UNITED STATES PATENT OFFICE

JOHN COOPER, OF INCHINNAN, SCOTLAND

ART OF PACKING INNER TUBES FOR PNEUMATIC TIRES

Application filed January 4, 1930, Serial No. 418,544, and in Great Britain January 17, 1929.

This invention relates to the art of packing pneumatic tire inner tubes of the ring-shaped type e. g., tubes of the type prepared on a ring-shaped mandrel, or moulded in a ring-shaped mould, and, when deflated, presenting when laid on a plane surface an annular ribbon.

Tubes of this type when folded diametrically with one half superimposed on the other may be coiled from one end into a roll having the configuration of a truncated cone.

The object of the invention is to provide a package comprising a tube of this type coiled into a conical roll and housed tightly in a hollow container of the same conicity as the roll, so that the surfaces of the roll and the container which are in frictional engagement are confined to the outer peripheral surface of the roll and the inner peripheral surface of the container.

In the drawings which illustrate the invention diagrammatically, Fig. 1 is a plan of a ring-shaped tube fully extended, Fig. 2 is a similar view showing the tube folded diametrically and partly rolled, and Fig. 3 a section showing the tube completely rolled and packed in a container.

The package shown comprises a tube 1 of the type described which is folded and coiled, as illustrated in Figs. 1 and 2, into a conical roll and housed tightly in a hollow container 2 having a base 3 and a lid 4 and being of the same conicity as the roll.

It will be seen from Fig. 3 that the surfaces of the roll and the container which are in frictional engagement are confined to the outer peripheral surface of the roll and the inner peripheral surface of the container.

The container is of hollow truncated conical formation and is of greater depth than the normal tube with which it is associated so that the end faces of the conically coiled tube 1 tightly fitted in the container are spaced from the base 3 and the lid 4.

If desired, suitable packing material may

be introduced between the tube and the lid so as to prevent endwise displacement of the tube relatively to the container.

The lid 4 and the base 3 are applied in known manner so as to render the package 50 hermetically sealed and light-tight.

I claim:

1. As an article of manufacture, a package comprising a ring-shaped pneumatic tire tube coiled into a conical roll, and a hollow container of truncated conical formation snugly housing said roll and being of the same conicity as said roll, so that the surfaces of said roll and said container which are in frictional engagement are confined to the 60 outer peripheral surface of said roll and the inner peripheral surface of said container.

2. As an article of manufacture, a package comprising a ring-shaped pneumatic tire tube coiled into a conical roll, a hollow container of truncated conical formation snugly housing said roll and being of the same conicity as said roll, so that the surfaces of said roll and said container which are in frictional engagement are confined to the outer peripheral surface of said roll and the inner peripheral surface of said container, and a base 65 and a lid for said container positioned so as to be clear of the end faces of said roll.

3. As an article of manufacture, a package 75 comprising a ring-shaped pneumatic tire tube coiled into a conical roll, a hollow container of truncated conical formation snugly housing said roll, said container being of the same conicity as, and being of greater depth 80 than said roll, and a base and a lid for said container positioned near the ends of said container as to be spaced from the end faces of said roll.

4. As an article of manufacture, a package 85 comprising a ring-shaped pneumatic tire tube coiled into a conical roll, a hollow container of truncated conical formation snugly housing said roll, said container being of the same conicity as, and of greater depth than 90

said roll, so that the surfaces of said roll and said container which are in frictional engagement are confined to the outer peripheral surface of said roll and the inner peripheral surface of said container, and a base and a lid for said container so positioned as to be spaced from the end faces of said roll, said base and said lid forming with said container hermetic and light-tight seals.

10 In testimony whereof I have signed my name to this specification.

JOHN COOPER.
